UNITED STATES PATENT OFFICE.

LAWRENCE L. WHITAKER AND CHARLES C. ISHMAN, OF WINDBER, PENNSYLVANIA.

DESIGN FOR A PIN.

53,758.

Specification for Design.

Patented Aug. 26, 1919.

Application filed March 22, 1919. Serial No. 284,508. Term of patent 14 years.

To all whom it may concern:

Be it known that we, LAWRENCE L. WHITAKER and CHARLES C. ISHMAN, citizens of the United States, residing at Windber, in the county of Somerset and State of Pennsylvania, have invented a new, original, and ornamental Design for Pins, of which the following is a specification, reference being had to the accompanying drawing, forming part thereof.

The figure is a plan view of the pin showing our new design.

We claim:

The ornamental design for a pin, substantially as shown.

LAWRENCE L. WHITAKER.
CHARLES C. ISHMAN.
